UNITED STATES PATENT OFFICE.

PHILIP LESSON, OF NEWARK, NEW JERSEY, ASSIGNOR TO LEO SCHLESINGER & CO., OF NEW YORK, N. Y.

CHILD'S RATTLE.

SPECIFICATION forming part of Letters Patent No. 276,251, dated April 24, 1883.

Application filed March 15, 1883. (No model.)

To all whom it may concern:

Be it known that I, PHILIP LESSON, of the city of Newark, county of Essex, and State of New Jersey, have invented a new and useful Improvement in Child's Rattle; and I do hereby declare that the following is a full and exact description thereof, reference being had to the accompanying drawings, and to the letters of reference marked thereon, making a part of this specification.

My invention relates to a child's toy-rattle constructed of sheet metal, and has for its object lessening the cost of manufacture and increasing the durability of the toy.

It consists in forming the device in two longitudinal divisions, each of which is stamped out of sheet metal into proper shape between suitable dies in a transversely-concave form, and in uniting the two divisions longitudinally by folding and clamping down the edges of the one upon the other, as hereinafter described.

In the accompanying drawings, Figure 1 is a plan view of the inner side of one division of the rattle. Fig. 2 is a longitudinal section through the finished rattle, at right angles to its seam, in line *xx* of Fig. 3; and Fig. 3 is a transverse section through the head of the rattle in line *yy* of Fig. 2.

Each division *A A* of the rattle is stamped or swaged out from a strip of sheet metal between suitable dies in a power-press, so as to embrace in the one piece the half of the entire length of the device, including its head and handle. Any suitable or ornamental configuration may be imparted to the division thus formed, and the two divisions may be stamped out between the same dies. One of the divi-

ions for each rattle is, however, formed with a narrow flat flange or rim, *c*, around its entire length, while the opposite division is formed with a corresponding flange, *e*, of twice the width. (See dotted lines, Fig. 1.) The two divisions, being brought together, are firmly united each to each, after inclosing between them one or more balls, *B B*, to form the complete rattle, by folding over the wide flange *c* of the one division upon the counterpart narrow flange *e* of the other division and tightly clamping the folded seam thus formed, so as to produce a firm unyielding joint.

The use of solder is thus dispensed with. The handle and head are formed in one continuous piece, so that the rattle is stronger than when these parts are jointed together, and as but one set of dies are required for stamping them and the operation of stamping and uniting the two stamped divisions may be performed by machinery, the finished toy can be rapidly produced at a very low cost, and yet with a highly finished and ornamented appearance.

I claim as my invention—

As a new article of manufacture, a child's rattle constructed of sheet metal in two longitudinal divisions, united at their edges by a simple folded seam, without solder or rivets, substantially in manner as herein set forth.

In testimony whereof I have signed my name to this specification in the presence of two subscribing witnesses.

PHILIP LESSON.
